METHOD OF PRODUCING FITTINGS IN THE FORM OF ADAPTERS OR THE LIKE

Eugene M. Cartwright, Woodbury, Conn., assignor to Chase Brass & Copper Co. Incorporated, Waterbury, Conn., a corporation

Application June 7, 1939, Serial No. 277,804

3 Claims. (Cl. 207—10)

This invention relates to improvements in methods of producing fittings in the form of adapters or the like for pipes, tubes and similar articles, and more particularly to methods of producing fittings suitable for interconnecting the threaded terminal of a pipe, pipe-fitting, tube, etc., with the unthreaded end of another pipe, fitting or tube.

One of the objects of the present invention is to provide a superior method for producing adapters for interconnecting threaded and unthreaded pipes, tubes, or fittings, whereby the adapters may be produced at a low cost for manufacture.

Another object of the present invention is to provide a superior method for producing adapters of the type referred to, whereby the said adapters may be produced free from cracks and flaws.

A further object of the present invention is to provide a superior method for producing adapters for interconnecting threaded and unthreaded pipes, tubes, and the like, whereby portions of the material of a relatively small and compact slug or blank may be displaced a relatively great distance to form an adapter without creating flaws or fissures therein.

A still further object of the present invention is to provide a superior method for producing adapters of the type referred to, whereby a relatively-long and thin tubular extension may be displaced from a relatively-small and readily handable slug or blank without occasioning undue wear upon the tools employed.

Still another object of the present invention is to provide an improved method for producing a superior adapter suitable for interconnecting the threaded terminal pipe, tube or fitting with the unthreaded terminal of a pipe, tube or fitting, and characterized by lightness of weight and superior resistance to distortion and denting.

Another object of the present invention is to provide a superior method of producing adapters of the type referred to, whereby substantially all of the materials of a blank may be shaped into an adapter without creating an undue amount of waste material requiring trimming-off.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purpose:

Fig. 1 is a view mainly in central-longitudinal

section and partly in elevation of two complementary die-members and a mandrel-member suitable for producing the adapters of the present invention, the said parts being shown in their re-tired positions and a slug or blank being shown in place upon the lower die-member;

Fig. 2 is a view corresponding to Fig. 1 but showing the two die-members closed and the mandrel-member in the position which it assumes at the instant of the starting of the extruding operation;

Fig. 3 is a similar view but showing the mandrel in the position which it assumes at the completion of the extruding operation;

Fig. 4 is a broken transverse sectional view taken on the line 4—4 of Fig. 3;

Fig. 5 is a similar view taken on the line 5—5 of Fig. 3;

Fig. 6 is a perspective view of a slug or first-stage blank suitable for the production of adapters;

Fig. 7 is a view partly in central-longitudinal section and partly in elevation of the second-stage blank;

Fig. 8 is a top or plan view thereof;

Fig. 9 is an under-end view thereof;

Fig. 10 is a view partly in central-longitudinal section and partly in elevation of an elbow-adapter which may be produced from the second-stage blank of Figs. 7 to 9 inclusive.

Fig. 11 is a similar view of a straight-line adapter which may be produced from a second-stage blank of the character shown in Figs. 7, 8 and 9;

Fig. 12 is a view partly in central-longitudinal section and partly in elevation of another form of second-stage blank from which another form of straight-line adapter may be produced in accordance with the present invention; and

Fig. 13 is a view partly in central-longitudinal section and partly in elevation of a finished straight-line adapter which may be produced from the second-stage blank of Fig. 12.

In Figs. 1 to 5 inclusive, of the accompanying drawings, is shown an apparatus suitable for carrying out the process of the present invention to produce fittings for tubes or pipes, preferably in the form of adapters. The apparatus referred to includes a die-member 20 provided with an extrusion-passage 21 extending therethrough and having a size and cross-sectional form corresponding to the desired size and cross-sectional form of the outside of the extension-portion of the adapter to be produced. Adapted to be alternately engaged with and re-tired out of engagement with the die-

member 20 is a die-member 22 having a passage 23 extending therethrough in axial alignment with the extrusion-passage 21 in the die-member 20. The passage 23, just referred to, is formed at its 5 end adjacent the die-member 20 with a polygonal enlargement 24 which, together with the adjacent portion of the passage 23 proper, substantially conforms in size and cross-sectional form to the desired exterior contours of the body-portion of 10 the adapter which it is desired to produce, all as will more fully hereinafter appear.

Cooperating with the die-members 20 and 22 is a mandrel-member generally designated by the reference character 25 and including a relatively-long 15 guide-portion 26 which corresponds in size and cross-sectional form to the desired size and cross-sectional form of the interior of the extension-portion of the adapter to be produced. The said guide-portion 26 projects outwardly from 20 a relatively-short and -thick displacing-portion 27 which is circular in cross-section and preferably has a taper extending inwardly and toward the guide-portion 26 and of a degree substantially corresponding to the taper of standard pipe- 25 threads.

The displacing-portion 27 of the mandrel-member 25 is located intermediate the guide-portion 26 and the body-portion 28 of the mandrel-member 25. The end of the said body-portion 28 adjacent the displacing-portion 27 provides a stop-portion 29 which is substantially perpendicular with respect to the axis of the mandrel-member 25 and which faces toward the guide-portion 26 and the displacing-portion 27 of the said mandrel. 30 At the junction point of the displacing-portion 27 and the stop-portion 29 the mandrel-member 25 is formed with a bevel-portion 30 for the purpose as will hereinafter appear.

To produce the adapters of the present invention a tubular slug or first-stage blank such as 40 31 (Figs. 1, 2 and 6) may be employed which preferably has at one end an annular axially-extending locating-flange 32. The exterior diameter of the tubular first-stage blank 31 is 45 such as to be freely received within the passage 23 in the die-member 22 and the internal diameter of the said blank is such as to receive the guide-portion 26 of the mandrel-member 25. As is shown particularly well in Figs. 1 and 2 the outside 50 diameter of the locating-flange 32 of the first-stage blank 31 is such as to substantially fit the extrusion-passage 21 in the die-member 20 so as to centralize the blank with respect to the said extrusion-passage 21 and also with respect to 55 the passage 23 in the die-member 22 and with respect to the mandrel-member 25.

While the two die-members 20 and 22 are separated from each other and the mandrel-member 25 is retired as illustrated in Fig. 1, the first-stage blank 31 is placed upon the said die-member 20 so as to be centralized by the entry of its locating-flange 32 into the adjacent end of the extrusion-passage 21, as shown. When placed upon the die-member 20 as just described, the 60 blank 31 is preferably at a red heat.

With the parts positioned as above described and as shown in Fig. 1, the die-member 22 is preferably first brought into engagement with the die-member 20, so that the major portion of 70 the first-stage blank 31 is located within the passage 23 in the die-member 22 and the mandrel-member 25 is then also moved to enter its guide-portion 26 into the blank 31, as is shown in Fig. 2. When the mandrel-member 25 reaches 75 the position in which it is illustrated in Fig. 2,

its guide-portion 26 will extend well below the lower face of the blank 31, in position to act as a guide for the portion of the said blank which is about to be extruded downwardly.

The continued movement of the mandrel-member 25 will, by virtue of the engagement of the displacing-portion 27 thereof with the upper-portion of the first-stage blank 31, force the metal of the lower portion of the said blank downwardly into the rink-like space provided between the 10 outer periphery of the guide-portion 26 of the mandrel-member 25 and the surface of the extrusion-passage 21 in the die-member 20. Substantially simultaneously, the material of the upper portion of the first-stage blank 31 will flow 15 upwardly in the ring-like space between the displacing-portion 27 of the mandrel-member 25 and the surface of the passage 23 in the die-member 22, until ultimately the material of the blank comes into engagement with the stop-portion 29 20 and the bevel-portion 30 of the said mandrel-member 25. Substantially at the same time, an intermediate portion of the blank 31 will be forced outwardly into the polygonal enlargement 24 of the die-member 22, all as illustrated in Figs. 25 25 and 5.

In the construction shown, both the guide-portion 26 of the mandrel-member 25 and the extrusion-passage 21 are of relatively great axial length, though not necessarily so, since the said 30 features, obviously, need be only sufficiently long to provide between them a ring-like extrusion-space to predetermine the interior and exterior shapes and sizes, respectively, of the extruded portion. 35

The action of the mandrel-member 25, in conjunction with the die-members 20 and 22, as above described, results in the formation of a second-stage blank, generally designated by the reference character 33, as is particularly well 40 shown in Figs. 7, 8 and 9. The said second-stage blank, as thus formed, includes a relatively-thin-walled extension-portion 34 and a relatively-heavy thick-walled body-portion 35. The said extension-portion 34 may be guided against lateral deflection during its formation as above described, by either or both the guide-portion 26 and the 45 surface of the extrusion-passage 21.

The body-portion 35 above referred to is formed with a polygonal wrench-receiving portion 36 upon 50 its exterior and has a tapered thread-receiving recess or socket 37 formed therein and conforming in shape to the displacing-portion 27 of the mandrel-member 25. The socket 37 terminates at the outer end of the said body-portion in a chamber 55 38 conforming to the bevel-portion 30 of the mandrel-member 25. The outer end of the extension-portion 34 of the second-stage blank 33 may now, if desired, be trimmed along the line 60 39 (Fig. 7) to provide a smooth and finished end-face for the blank.

After the second-stage blank 33 has been formed as above described, the die-members 20 and 22 and the mandrel-member 25 may be restored to the positions in which they are indicated in Fig. 1 65 to thus permit the removal of the said blank 33.

Various mechanisms may be employed for causing relative movement between the die-members 20 and 22 and the mandrel-member 25 though it may be here mentioned that a double-action 70 power-press has been found suitable.

The thread-receiving socket 37 in the body-portion 35 of the second-stage blank 33 after its removal from the tools, may be provided with threads 40 (Fig. 10) and the extension-portion 34 75

may be bent at a right angle, for instance, to form an arcuate extension-portion 41 of an elbow-adapter generally designated by the reference character 42 in Fig. 10. The said elbow-adapter 5 42 includes a relatively-heavy body-portion 43 in which the threads 40 before referred to are formed and which is provided at its inner end with a polygonal wrench-receiving portion 44. The outer 10 terminal of the arcuate extension-portion 41 may be expanded or bellmouthing to provide a tube-receiving socket 45 as is shown in Fig. 10.

As thus produced, the elbow-adapter 42 is of double-female character and is suitable for providing a right-angled connection between a 15 threaded pipe, tube or pipe-fitting engaged with the threads 40, and an unthreaded tube, pipe or fitting which may be received in the tube-receiving socket 45 and sweat-soldered therein in a manner now common in the art of pipe-fitting.

20 Instead of converting the second-stage blank 33 into the elbow-adapter 42, the said blank may be converted into a double-female straight-line adapter generally designated by the reference character 46 and illustrated in Fig. 11 of the 25 accompanying drawings. The adapter 46, just referred to, includes a relatively-heavy body-portion 47 corresponding to the body-portion 43 of the elbow-adapter 42 and, like the same, provided with a threaded female-socket 48 adapted 30 to receive a threaded pipe, tube or pipe-fitting. Also like the body-portion 43 of the elbow-adapter 42, the straight-line adapter 46 is provided with a polygonal wrench-receiving portion 49.

The straight-line adapter 46 also includes a 35 relatively-thin-walled extension-portion 50 which is bellmouthing at its lower end to provide a tube-receiving socket 51 adapted to receive and have sweat-soldered into it, the terminal-end of an unthreaded pipe, tube or pipe-fitting.

40 The showing of Figs. 12 and 13 relates to a short straight-line adapter which may be produced by tools similar to those before described in connection with the form of the present invention shown in Figs. 1 to 5 inclusive, to provide a second-stage blank generally designated by the 45 reference character 52 in Fig. 12. The said second-stage blank 52 includes a body-portion 53 having an external polygonal wrench-receiving portion 54. The said body-portion 53 is also provided with a tapered thread-receiving socket 55 and with a chamfer 56. Projecting from the inner end of the body-portion 53 is an extension-portion 57 which may be extruded in the same 50 manner as has been described in connection with the extension-portion 34 of the second-stage blank 33. The second-stage blank 52 may have its extension-portion 53 trimmed off along the line 58 (Fig. 12) to provide a smooth terminal-60 edge.

The second-stage blank 52 may be converted into a finished straight-line adapter like that shown in Fig. 13 by providing the thread-receiving socket 55 thereof with threads 59 and by 65 counterboring the extension-portion 57 thereof to provide a tube-receiving socket 60 adapted to snugly receive the unthreaded terminal of a pipe, tube or pipe-fitting, any of which may be sweat-soldered in place in said socket 60. The counterboring, to produce the tube-receiving socket 60, 70 results in the formation of a stop-shoulder 61 in the finished straight-line adapter 62 of Fig. 13. The completed straight-line adapter 62 thus includes a body-portion 63 in which the threads 59 75 are formed, a chamfer 64, a polygonal wrench-

receiving portion 65 and a tubular extension-portion 66 in which the socket 60 is formed.

The adapters of the present invention may be formed of a wide variety of materials though a copper and copper-base material is preferred 5 for many reasons among which may be mentioned its corrosion-resistance and its solderability.

Instead of forming internal threads in the body-10 portions of the adapters, the said body-portions may obviously be provided with external threads. Similarly the extension-portions of the adapters 15 may be sized to fit within an unthreaded pipe or the like rather than having such pipe or the like telescoped into the said extension-portions.

By employing an extrusion operation in producing the adapters above described, not only is the wear and tear upon the tools employed very much minimized, but an appreciable saving in power may be effected and the resultant adapter 20 rendered homogeneous and free of flaws and fissures. Furthermore, the resultant adapter is rigid and markedly resistant to denting and other impairments which might result from rough handling.

The invention may be carried out in other 25 specific ways than those herein set forth without departing from the spirit and essential characteristics of the invention, and the present embodiments are, therefore, to be considered in all respects as illustrative and not restrictive, and 30 all changes coming within the meaning and equivalency range of the appended claims are intended to be embraced therein.

I claim:

1. A method of producing fittings in the form 35 of adapters or the like for interconnecting pipes or similar articles, the said method comprising: substantially confining a metal tubular blank in a die-cavity having a ring-like extrusion-opening leading therefrom; bringing into operative relationship to said metal tubular blank a mandrel-member having a guide-portion and a displacing-portion respectively of smaller diameter than the diameter of the said extrusion-opening and the outside diameter of the said metal tubular 40 blank; extending the guide-portion of the said mandrel-member through the said metal tubular blank and into the said extrusion-opening; and bringing the displacing-portion of the said mandrel-member into engagement with the said metal tubular blank and causing it to perform a metal-displacing operation thereon to produce a hollow body-portion having its wall formed of sufficient thickness and length to carry a number of threads thereon for threaded connection of the 45 said body-portion to a threaded end of a pipe or the like, and to substantially-simultaneously produce in the said metal-displacing operation extrusion of displaced metal through the said extrusion-opening and around the guide-portion of 50 the said mandrel-member to form a tubular extension-portion projecting from the said body-portion.

2. A method of producing fittings in the form 55 of adapters or the like for interconnecting pipes or similar articles, the said method comprising: substantially confining a metal tubular blank in a die-cavity having a ring-like extrusion-opening leading therefrom; bringing into operative relationship to said metal tubular blank a mandrel-member having a guide-portion and a displacing-portion respectively of smaller diameter than the diameter of the said extrusion-opening and the outside diameter of the said metal tubular 60 blank; extending the guide-portion of the said 65 mandrel-member through the said metal tubular blank and into the said extrusion-opening; and bringing the displacing-portion of the said mandrel-member into engagement with the said metal tubular blank and causing it to perform a metal-displacing operation thereon to produce a hollow body-portion having its wall formed of sufficient thickness and length to carry a number of threads thereon for threaded connection of the 70 said body-portion to a threaded end of a pipe or the like, and to substantially-simultaneously produce in the said metal-displacing operation extrusion of displaced metal through the said extrusion-opening and around the guide-portion of the said 75 mandrel-member to form a tubular extension-portion projecting from the said body-portion.

mandrel-member through the said metal tubular blank and into the said extrusion-opening; and bringing the displacing-portion of the said mandrel-member into engagement with the said metal tubular blank and causing it to perform a metal-displacing operation thereon to produce a socket-like body-portion for receiving an end of a pipe or the like, and to substantially-simultaneously produce in the said metal-displacing operation extrusion of displaced metal of the said blank through the said extrusion-opening and around the guide-portion of said mandrel-member to form a tubular extension-portion projecting from the said socket-like body-portion.

15. 3. A method of producing fittings in the form of adapters or the like for interconnecting pipes or similar articles, the said method comprising: substantially confining a metal tubular blank in a die-cavity having a ring-like extrusion-opening leading therefrom; bringing into operative relationship to said metal tubular blank a mandrel-member having a guide-portion and a displacing-portion respectively of smaller diameter than the diameter of the said extrusion-opening and the

outside diameter of the said metal tubular blank; extending the guide-portion of the said mandrel-member through the metal tubular blank and into the said extrusion-opening; and bringing the displacing-portion of the said mandrel-member into engagement with the said metal tubular blank and effecting a metal-displacing operation of a character to cause flow of metal in the direction of the said extrusion-opening and also between the said die-cavity and the said displacing-portion in the direction opposite the said extrusion-opening to produce a hollow body-portion having its wall formed of sufficient thickness and length to carry a number of threads thereon for threaded connection of said body-portion with a threaded end of a pipe or the like, and to also produce in the said metal-displacing operation extrusion of displaced metal of the said blank through the said extrusion-opening and around the guide-portion of the said mandrel-member to form a tubular extension-portion projecting from the said body-portion.

EUGENE M. CARTWRIGHT.
